HAROLD J. CORDONNIER AND CORBAN H. ZILER, OF CARTHAGE, MISSOURI

COFFIN-LOWERING DEVICE

Application filed May 13, 1939. Serial No. 362,690.

This invention relates to coffin lowering devices and has for one of its objects to provide an apparatus of this character which will be simple in construction, comparatively inexpensive to manufacture and more efficient in use than those which have been heretofore proposed.

A further object of the invention is to provide means in a coffin lowering apparatus for facilitating the placing of the coffin in position for lowering into a grave.

With the above and other objects in view which will appear as the description proceeds, the invention consists in the novel 15 details of construction, and combinations and arrangements of parts more fully herein-after disclosed and particularly pointed out in the appended claims.

Referring to the accompanying drawing 20 forming a part of this specification in which like reference characters designate like parts in all the views:

Figure 1 is a perspective view of a coffin 25 lowering device embodying the improvements constituting the present invention;

Figure 2 is an enlarged section view taken approximately on the plane indicated by the line 2—2 of Fig. 1; and

Figure 3 is a top plan view of the parts 30 shown in Fig. 2.

There is at present in comparatively wide use one or more forms of apparatus for lowering coffins into graves which apparatus in general comprises a substantially rectangular frame work adapted to be positioned about the mouth of the grave, said frame work including rotatable side rods or bars, the rotation of which may be controlled through suitable mechanism enclosed in 35 housings at the ends of the said bars. Canvas or other suitable straps have their ends secured to these side bars and are wound thereon through the rotation of the bars in one direction so as to form transversely 40 extending supports upon which the coffin is placed, and by means of which it may be lowered into the grave through the reverse rotation of the side members of the frame.

It frequently happens, however, that the 45 coffins are quite heavy and it is difficult for

the pall-bearers or grave attendants to place the coffin in position upon the supporting straps. The present invention provides means whereby one end of the coffin may be placed in position over one end of the frame 55 and supported in such a manner that the coffin may be pushed or slid longitudinally of the grave into position above the said straps. Upon release of the control mechanism of the rotatable side bars, the members constituting the present invention, 60 which are preferably carried by the said bars, move downwardly and out of the way of the descending coffin, permitting the latter to be lowered on the flexible straps in 65 the usual manner.

Referring more particularly to Fig. 1 of the drawings, there is illustrated one well known form of apparatus for lowering a coffin which comprises a frame work composed of the end rods or bars 5 and the side rods or bars 6 which are rotatable, under the control of suitable mechanism forming no part of the present invention, but which is enclosed in suitable housings such as 7 70 arranged at the corners of the frame. A control handle 8 is provided for governing the action of the control mechanism within the housing 7, whereby the side rods 6 may be permitted to rotate or stopped at 75 will, in the well known manner. Canvas or other suitable flexible straps 9 span the space between the side bars 6 and constitute supports for the coffin during the lowering operation. 80

In order that coffins may be more readily brought to position upon the straps 9, the present invention provides transversely extending supporting elements 10 which are shown in detail in Figs. 2 and 3. As will be 85 clear from these figures, a collar 11 is secured to the rotatable side rods or bars 6, as for example, by means of set screws 12. Straddling this collar 11 is the bifurcated end 13 of a supporting member 14 which terminates 90 in the opposite direction in a stud or pin 15 upon which is journalled a roller 16. A headed screw 17 may be provided for retaining the roller in place, as will be clear from 95 the drawings. 100

The bifurcated end 13 of the member 14 is journalled upon the rotatable side member 6 for rotation relative thereto, and in order to prevent such rotation in one direction, whereby the supporting members may be maintained in the horizontal positions shown in Fig. 1, any suitable form of ratchet or one way clutch mechanism may be provided. In the embodiment of the invention shown in the drawings, this clutch mechanism comprises a roller 18 housed within the bifurcated ends 13 of the member 14, and adapted to engage with the outer surface of the collar 11 and with the rear face 19 of the bifurcation of the member 14, as will be clear from Fig. 2. The said roller 18 is normally pressed upwardly into wedging engagement with these two surfaces by means of a spring 20 whereby relative rotation between the members 6 and 14 in one direction may be prevented as will be readily understood.

In order that the clutch roller 18 may be disengaged when it is desired to properly position the supporting elements 10, there is provided a releasing pin 21 which extends through and is slidably mounted in an aperture 22 formed in the upper wall of the member 14. The inner end of the pin 21 is adapted to engage the clutch roller 18 so that by depressing the said pin 21, the said roller may be moved out of wedging engagement with the surface of the collar 11, and the surface 19 whereupon the member 14 may be free to swing in either direction. The clutch may be held in this released position by rotation of the release pin 21, when in depressed condition such rotation serving to bring one end of a transverse pin 23 under the shoulder 24 as shown in Fig. 2 whereby the return of the roller 18 and pin 21 by the spring 20 is prevented.

As many of these supporting devices may be employed as are necessary or desired, four having been shown in Fig. 1 of the drawings. It will be understood that with the supporting elements 10 arranged as shown in said Figure 1, one end of a coffin may be introduced endwise over the frame of the lowering device to a position where such end will rest upon the first pair of rollers 16, whereupon the said coffin may be rolled or slid longitudinally to final position over the mouth of the grave. Upon release of the control mechanism contained in the housings 7, the side bars 6 will be slowly rotated in opposite directions and will carry with them the supporting members 10 thereby transferring the weight of the coffin to the flexible straps 9. When the members 10 reach a vertical pendant position the weight thereof will serve to maintain them in that position since the rotation of the side bars 6 is in such direction as to release the clutches, and therefore the members 10 will not be brought around to such a position that they could contact

with and interfere with the lowering of the coffin.

While one form of the invention has been illustrated and described, it is obvious that those skilled in the art may vary the details of construction as well as the precise arrangement of parts without departing from the spirit of the invention and therefore, it is not wished to be limited to the above disclosure except as may be required by the claims.

What is claimed is:

1. The combination with a coffin lowering device comprising rotatable lowering elements and flexible members carried thereby for supporting the coffin, of means also carried by said rotatable elements for initially supporting the coffin above said flexible members.

2. The combination with a coffin lowering device comprising rotatable lowering elements and flexible members carried thereby for supporting the coffin, of means also carried by said rotatable elements for initially receiving the weight of the coffin and permitting it to be slid into position above said flexible members.

3. In a coffin lowering apparatus, the combination of spaced rotatable lowering elements; flexible coffin supporting members carried thereby; and transversely extending rollers also carried by said rotatable elements for initially receiving said coffin and permitting it to be rolled into position above said flexible members.

4. In a coffin lowering apparatus, the combination of spaced rotatable lowering elements; flexible coffin supporting members carried thereby; transversely extending rollers also carried by said rotatable elements for initially receiving said coffin and permitting it to be rolled into position above said flexible members; and one-way clutch connections between said rotatable elements and said rollers.

In testimony whereof we affix our signatures.

HAROLD J. CORDONNIER.
CORBAN H. ZILER.
